UNITED STATES PATENT OFFICE.

GEORGE A. JOHNSON, OF CHICAGO, ILLINOIS, ASSIGNOR TO WILLIAM H. MINER, OF CHAZY, NEW YORK.

STOP-CASTING.

1,259,994.

Specification of Letters Patent. Patented Mar. 19, 1918.

Application filed September 20, 1916. Serial No. 121,126.

To all whom it may concern:

Be it known that I, GEORGE A. JOHNSON, a citizen of the United States, residing at Chicago, in the county of Cook and State 5 of Illinois, have invented a certain new and useful Improvement in Stop-Castings, of which the following is a full, clear, concise, and exact description, reference being had to the accompanying drawings, forming a 10 part of this specification.

This invention relates to improvements in stop castings.

Objects of the invention are to provide a stop casting for draft riggings wherein the 15 casting is of maximum strength for a unit of weight; wherein the casting may be made free from casting and annealing strains; which obviates the use of cores in the casting operation; wherein the casting is provided with hollow stops without the necessity of horizontally extending strengthening flanges therewithin to thus facilitate the molding operation; and wherein the casting 20 is provided with large bearing and wearing 25 surfaces.

The invention furthermore consists in the improvements in the parts and devices and in the novel combinations of the parts and devices herein shown, described and claimed.

30 In the drawing forming a part of this specification, Figure 1 is a side elevation of an improved stop casting embodying my invention. Figs. 2 and 3 are horizontal sectional views taken on the lines 2—2 and 35 3—3, respectively, of Fig. 1. And Figs. 4, 5, 6 and 7 are vertical sectional views taken on the lines 4—4, 5—5, 6—6 and 7—7, respectively, of Fig. 1.

In said drawing, the casting which I have 40 illustrated is of the tandem type and as shown, comprises a web of metal having a series of vertical convolutions A, B, C, D, E, F, G, H, and I forming the stops 10, 11, 12, 13, 14, 15, 16 and 17 and the follower 45 receiving recesses therebetween. It will be noted that each of the vertical convolutions A, C, E, G and I are open to the back of the casting and the remaining convolutions B, D, F and H, open to the front or inner 50 face of the casting. Said convolutions are formed by weaving or bending the metal back and forth, as will be understood from an inspection of Figs. 2 and 3. Intermediate each main and limiting stop, the web 55 of the casting is provided with a pair of

depressions or pockets 18—18, the bottoms of which are in the back plane of the casting and form the riveting areas, said pockets being sufficiently enlarged to receive the riveting tool. At the ends the casting is 60 provided with additional riveting areas in the form of depressions 19—19. Intermediate the main stops 10 and 13, and 14 and 17, the web of the casting is provided with a horizontally extending portion 20 to thus 65 form the upper guides for the followers that reciprocate between the stops. Above said horizontal portion 20 the web of the casting is extended in a general vertical direction, then rearwardly to the back plane of 70 the casting in a horizontal portion 21. Similarly, at the bottom of the casting the web is extended rearwardly to the back plane of the casting, as indicated at 22. By referring to Fig. 2, it will be noted that the 75 center post forming the intermediate main stops 13 and 14, is considerably deeper than either of the end stops and the top portion of the casting is tapered toward either end as indicated at 23—23, to permit the yoke 80 of the draft rigging to swing radially about said center post when the car is passing over curves.

In order to provide great strength in the casting against longitudinal and transverse 85 strains, and at the same time to retain large bearing and wearing surfaces both on the outer and transverse faces of the stops and the follower guiding surfaces, the web of the casting is provided with a series of horizontally extending, somewhat shallow flutes 90 24, 25, 26, 27 and 28. It will be noted that the horizontally extending flutes 24, 26 and 28 extend throughout the entire length of the casting, both over the outer faces of the 95 stops as indicated at 29—29, along the vertical faces of the main and limiting stops as indicated at 30—30, and across the follower guiding surfaces or bottoms of the vertical convolutions B, D, F and H, as indicated at 31—31. The remaining flutes 25 and 27 also extend across the outer and transverse faces of the stops, but are omitted where the same cross the rivet pockets 105 18—18. As clearly appears from Figs. 4, 5, 6 and 7, the flutes are in the form of shallow, curved grooves on the inner face of the casting and thereby leave a maximum wearing flat surface 32 on the inner face of the stops and follower guiding surfaces, and 110

a maximum bearing area as indicated at 33-33 on the transverse portions of the stops and against which the followers normally bear.

5 By means of the fluting above described, in combination with the vertical convolutions, a casting of great strength is obtained without sacrificing the desirable large wearing and bearing area and furthermore, the 10 casting is so constructed that the web thereof is of substantially the same thickness throughout its entirety and the casting may be made without the use of cores since there are no undercut surfaces. By maintaining 15 the uniformity of thickness of the web, it is obvious that the casting operation is simplified since all portions of the casting will cool at the same rate, thus minimizing casting strains. Similarly in the annealing operation, all portions of the metal can be annealed at the same rate, thus producing a 20 casting free from the defects commonly encountered in devices of this character. In addition to the foregoing, it is obvious that 25 by weaving the metal inwardly and outwardly in the form of vertical convolutions, as above described, a casting of relatively great thickness is obtained without actually employing any thick sections of metal.

30 I claim:

1. A stop casting for draft riggings having a web of substantially uniform thickness throughout and provided with a series of vertical convolutions forming the 35 stops and a series of strengthening flutes, said flutes being arranged horizontally and extending across the faces of the stops.

2. As an article of manufacture, a stop casting having a web provided with a series of vertical convolutions, alternate convolutions being open to the back of the 40

casting and the remaining convolutions open to the front thereof, said casting being provided also with a plurality of horizontally extending flutes on the inner face 45 thereof.

3. As an article of manufacture, a stop casting having a web provided with a series of vertical convolutions, alternate convolutions being open to the back of the 50 casting and the remaining convolutions open to the front thereof, said casting being provided also with a plurality of horizontally extending flutes on the inner face 55 thereof, some of said flutes extending continuously from end to end of the casting and following the contour of the inner face thereof throughout.

4. As an article of manufacture, a tandem stop casting having a web of substantially uniform thickness throughout and provided with a series of vertical convolutions forming main and limiting stops, the vertical convolution at the center of the casting forming the intermediate main 60 stops being deeper than the convolutions forming the end main stops, the web of said casting being provided with a plurality of horizontally extending flutes, the latter extending across the inner faces of the stops 65 and also across the transverse faces of the stops, the web of the casting being provided also with a series of pockets intermediate the stops to form riveting areas. 70

In witness that I claim the foregoing 75 I have hereunto subscribed my name this 18th day of Sept., 1916.

GEORGE A. JOHNSON.
